HEART-SHAPED COMPARTMENTED TRAY

Hugh R. Weiss, Montclair, N.J., assignor to The Pantasote Company, Passaic, N.J., a corporation of New Jersey

Filed Dec. 1, 1961, Ser. No. 67,812

Term of patent 14 years

(Cl. D58—13)

I claim:

The ornamental design for a heart-shaped compartmented tray, as shown.
